UNITED STATES PATENT OFFICE.

CARL ALBERT HIRTH, OF CANNSTATT, NEAR STUTTGART, GERMANY, ASSIGNOR TO
FORTUNA-WERKE ALBERT HIRTH, OF CANNSTATT, GERMANY.

MACHINE FOR SKIVING LEATHER.

1,348,221.

Specification of Letters Patent.

Patented Aug. 3, 1920.

Application filed September 8, 1911. Serial No. 648,346.

To all whom it may concern:

Be it known that I, CARL ALBERT HIRTH, a citizen of the German Empire, residing in Cannstatt, near Stuttgart, Württemberg, in 5 said Empire, have invented certain new and useful Improvements in Machines for Skiving Leather, of which the following is a specification.

This invention relates to improvements in 10 leather skiving machines.

In machines for skiving or splitting leather and the like, the leather, as is well known, is fed between a feed roller or the like and a pressure-member, and the shape 15 of the skiving is altered by suitably adjusting the pressure-member. In order to obtain an oblique skiving, for example, the usual practice has been to adjust the slanting position of the pressure member with relation to 20 the ring-knife by means of an adjusting mechanism, and to adjust the height of the pressure-member with relation to the knife by another adjusting mechanism.

As the alteration of the slanting position 25 of the pressing surface also alters the height of the several parts of the pressing surface with relation to the knife, it was necessary, with the adjusting devices heretofore used, when readjusting the slanting position of 30 the pressure-member—that is to say, when altering the angle or length of the skiving—to make an adjustment not only with the mechanism for adjusting the slant but also with that for adjusting the height. Hence, 35 the adjustment required not only considerable time but also skill.

For instance if, in adjusting the slant of the pressure-member the height of the pressure-member were not simultaneously ad- 40 justed to a sufficient extent, it might easily happen that the pressure member would come in contact with the knife and impair its cutting edge.

The object of this invention is to render 45 the slant adjustment independent of the vertical or height adjustment, and vice versa, in such a manner that the slant or length of the skiving can be altered by simply adjusting the slant adjustment of 50 the pressure-member alone, without altering the adjustment for the thickness of the edge of the skiving. This is effected by arranging the axis about which the pressure-member is adapted to swing for the slant adjust- 55 ment, so that instead of that axis being, as

formerly, situated essentially outside of the pressure-surface, it may possibly touch that pressure-surface itself, namely at one of the lateral boundaries of same. In order that the manipulation of the work-piece may not 60 thereby be interfered with, it is advisable to mount the pressure-member in such portions of the machine as to insure a sufficient distance from the pressure-surface, or the path of the work.

In the accompanying drawing the invention is illustrated,

Figure 1 showing a side-elevation, in partial section, of the pressure-mechanism and ring-knife, seen at right angles to the axis 70 of the knife, and

Fig. 2 is a vertical transverse section along the line A—B of Fig. 1, taken at right angles to the axis of the knife and showing also the feed-roller, not seen in Fig. 1. 75

Similar letters of reference indicate corresponding parts throughout the several figures of the drawings.

The only portions of the feed-device here represented are the pressure-member and 80 the method of attaching same and adjusting it with relation to the rotary ring-knife *a*, having a sharpened edge. The feed-roller is indicated at *b*¹. The construction and operation of the same are well-known in the 85 art, and require no detailed description. The pressure-member consists of a roller *b* which is adapted to be adjusted vertically in an arm *e* of the machine by means of the slide-piece *d*.

To enable the roller *b* to be obliquely ad- 90 justed in the vertical plane of Fig. 2, the slide-piece *d* is provided with an arc-shaped guide-surface *f*—shown in section in Fig. 1, the center of which is situated in or as close 95 as possible to the edge *c* of the pressure-roller *b*. For the purpose of adjusting the slant of the roller *b*, that portion *g* of the roller-carrier which is guided along the surface *f*, is provided with teeth which are en- 100 gaged by a worm *h* adapted to be rotated by means of the button *i*. To enable the guide-device to be locked, a side-cheek *k* may be pressed against the part *g* of the roller-carrier by means of the clamping-screw *m*. 105

The mechanism for changing the pres- 110 sure-roller *b* for different classes of work is preferably arranged in the swinging por- tion *g*, guided by the surface *f*, so that the adjusting mechanism remains the same for

all rollers. For example, the roller *b* is mounted at one end in the roller-carrying portion *g* at *o*, and at the other end in an arm *p*, which is adapted to be rotated about 5 the tube *g* (secured in the part *g*) and which can be slipped over said tube when the yoke *r* has been swung upwardly on its pivots *s*. In drawing out the arm *p* on the tube *g*, so that the shaft *t* of the pressure-roller *b* clears 10 its bearing in the arm *p*, a helical spring *v* which is supported against a spring-plate *w* secured in the tube *g*, is compressed by the spring-plate *u*, which is secured by means of a stem to the arm *p*. The arm *p* 15 may now be turned aside so that the roller *b* can be changed and the parts replaced, the spring *v* holding it firmly in any desired position.

It is not necessary for the pressure-roller 20 *b* to be positively operated, as it might run free with the work; nevertheless a ball-joint connected with a driving piece *x* is represented in the drawing. But it is not at all 25 essential to the invention that a roller *b* should be used as the pressure-member, as any other pressure-member, for instance a simple stationary presser-foot might be used.

It will be clearly evident that by the vertical or height-adjusting mechanism, the 30 position of the point *c* can always be adjusted with relation to the edge of the ring-knife in a perfectly definite manner, and that this adjustment is not altered by altering 35 the slanting position of the roller *b*. Thus for a definite thickness of the edge of the leather or other work under treatment the vertical or height-adjustment can be obtained once for all by means of a single adjustment, while the slant or width of the 40 skiving can be modified as desired, without affecting this adjustment; or in other words, only a single adjusting mechanism is needed for each of the two kinds of adjustment 45 (vertical or slant).

I claim:

1. A machine for skiving leather, comprising a ring-knife, a pressure-member for the work fed thereto, having a work contacting surface conforming to the cutting 50 edge of said knife, and an adjustable carrier for said pressure-member having an axis of adjustment located in the surface of contact between such member and the work and at 55 a lateral edge of said surface of contact.

2. A machine for skiving leather, comprising a ring-knife, a pressure-member for the work fed thereto having a work-contacting surface conforming to the cutting-

edge of said knife, and an adjustable carrier 60 for said pressure-member having an axis of adjustment substantially parallel to the axis of said knife and located in the surface of contact between said member and the work and at a lateral edge of said surface of contact. 65

3. A machine for skiving leather, comprising a ring-knife, a pressure-member, means for swinging said member in a plane at right angles to the direction of feed while 70 simultaneously preserving the distance of a part of said member from said knife, said means comprising a support having a curved 75 guide, and a carrier for said member adjustable in said guide, and an operating-device engaging said carrier.

4. A machine for skiving leather, comprising a ring-knife, a pressure-member for the work fed thereto having a work contacting surface conforming to the cutting 80 edge of said knife, an adjustable carrier for said pressure-member having an axis of adjustment located on the surface of contact between such member and the work and at a lateral edge of said surface of contact, and 85 a support for said carrier movable toward and away from the knife.

5. In a machine for skiving or splitting leather and other materials, the combination, 90 with a feed-mechanism, of a rotary ring-knife, a pressure-roller, a roller-carrying portion having an arc-shaped guide-piece at its upper end, adapted to swing the pressure-roller angularly relatively to said knife while simultaneously preserving the distance 95 of a part of said pressure-roller therefrom, means for adjusting the roller-carrying portion in a plane at right angles to the direction of the feed, and means for locking it after adjustment. 100

6. In a machine for skiving or splitting leather or other materials, the combination, with a feed-mechanism, of a rotary ring-knife, a pressure-roller, a roller-carrying portion, a movable arm on the same, means 105 for guiding the movable arm until clear of the shaft of the pressure-roller for permitting the interchange of one pressure-roller for another, and a yoke pivoted to the roller-carrying portion and adapted for locking or 110 releasing the movable arm.

In testimony that I claim the foregoing as my invention I have signed my name in presence of two subscribing witnesses.

CARL ALBERT HIRTH.
